DESIGN FOR A DRESS

Herbert M. Harris, New York, N. Y.

Application March 19, 1941, Serial No. 99,682

Term of patent 3½ years

To all whom it may concern:

Be it known that I, Herbert M. Harris, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the wide ribbon belt having large contrasting buttons down each side thereof in association with the matching buttons down the front of the blouse section, as shown.

I claim:

The ornamental design for a dress, as shown and described.

H. M. HARRIS.
